[57] CLAIM

The ornamental design for a tree waterer, as shown.

DESCRIPTION

FIG. 1 is a perspective view of a tree waterer showing my new design;

FIG. 2 is a reduced rear elevational view thereof;

FIG. 3 is a side elevational view thereof;

FIG. 4 is a top plan view thereof; and,

FIG. 5 is a bottom plan view thereof.

The tube has been shown broken away in FIGS. 1-3 to indicate indeterminate length.
